UNITED STATES PATENT OFFICE.

NICHOLAS POWER, OF BROOKLYN, NEW YORK, ASSIGNOR TO NICHOLAS POWER COMPANY, OF NEW YORK, N. Y., A CORPORATION OF DELAWARE.

SIGNAL DEVICE FOR FILM-MAGAZINES.

1,208,647.

Specification of Letters Patent. Patented Dec. 12, 1916.

Application filed February 7, 1914. Serial No. 317,301.

To all whom it may concern:

Be it known that I, NICHOLAS POWER, a citizen of the United States, and a resident of Brooklyn, in the county of Kings and State of New York, have invented certain new and useful Improvements in Signal Devices for Film-Magazines, of which the following is a specification.

This invention relates to improvements in indicators for film magazines for moving picture machines and has for its object to provide an indicator which is especially adapted to the lower or receiving magazine of a moving picture machine for the purpose of indicating whether or not the film is being properly wound on the film reel.

A further object of the invention is to provide an indicator of this class which is so designed that upon the breaking of the film a signal will be sounded calling the operator's attention so that he may stop the machine, or otherwise remedy the fault before serious damage can occur.

A further object of the invention is to provide an indicator of this class which will not lessen the fireproofing qualities of the magazine and which may be applied to machines already in use without modification of the existing magazine structure.

In the accompanying drawings, I have illustrated a preferred embodiment of my invention, and in said drawings, Figure 1 is a general view of a moving picture machine particularly the driving mechanism for the receiving reel; Fig. 2 is a perspective view of the receiving magazine detached from the machine with its door open to show the construction whereby the indicator is driven from the reel shaft; Fig. 3 is an enlarged detail view of the indicator showing a portion of the outer face of the magazine door; Fig. 4 is a vertical section through the indicator and a portion of the magazine.

Referring now to the drawings, in which like characters indicate like parts throughout the several views, the numeral 1 indicates the projecting mechanism or head of the machine, which may be of any preferred construction and which embodies a continuously rotating driving shaft here shown as the vertical shaft 2. Driven from this shaft by means of suitable gearing is the pulley wheel 3 which drives through the belt 4 the driving pulley 5 of the receiving

reel 6 for the film. The receiving reel is mounted on the driving shaft of the pulley 5 within the lower magazine 7 in the usual manner, and is held on the shaft by means of the pivoted dog 8 mounted in the end of the shaft so as to be turned to the radial position shown in Figs. 2 and 4 when the reel is on the shaft. As the reel increases in size the film will be wound more rapidly and break the film unless means are provided to permit the belt to slip and relieve the tension on the film. For this purpose the driving belt 4 is of a length to be quite slack when free and is held in driving engagement with the pulley 5 by means of a belt-tightening roller 9 mounted in the end of an arm pivoted on the reel shaft and held against the belt by a spring 10. The belt tightener is controlled by an arm 11 within the magazine which carries a guide spool 75 for the film and is connected by a suitable crank and lever mechanism with the arm of the belt tightening pulley. The film is trained over the spool in the manner shown in Fig. 1 so that as the film is tightened by 80 the increasing winding tension the arm 11 will be drawn toward the center of the magazine and thereby relieve the tension of the belt.

In a machine of this class it is desirable 85 that all parts of the mechanism, particularly the magazines for the film, shall be kept tightly closed throughout the exhibition so as to avoid as far as possible the liabilities of the highly inflammable film becoming ignited. As long as the film is intact the winding mechanism just described will insure its proper winding without attention from the operator, but should the film break, as it may do through poorly cemented joints, or for other reasons, it will 90 obviously be no longer wound on the reel, and as the mechanism and reel are inclosed the operator will not be aware of the failure of the winding mechanism until a sufficient 95 length of film is piled up to clog the machine or otherwise interfere with the exhibition.

The purpose of said invention is to indicate to the operator the progress of the 105 winding and to give notice to the operator by suitable signal should the film break. The normal position of the operator is on the side of the machine toward which the magazine doors open. It is therefore neces- 110

sary to provide the signal device on this side of the machine. The signal device comprises a dial or flange disk 12 attached to the outer face of the magazine door 13 at its center. At the center of the dial a bearing is provided for a spindle 14 which projects through the door and has attached to its inner end a claw or clutch member 15 which is adapted to engage the dog 8 when the door is closed as shown in Fig. 4. On the end of the shaft and in the flange disk 12 a cross bar 16 is attached and pivoted to the opposite ends of the cross bar are shoes 17 having pointed ends which are normally just clear of the inner surface of the flange of the disk 12. This surface is provided throughout its circumference with fine serrations 18 as shown more particularly in Fig. 3.

20 The operation of the device is as follows: When the magazine is closed driving engagement is established between the shaft of the reel and the spindle of the indicator so that the indicator will be rotated in synchronization with the reel when the operator may determine by observing the indicator whether or not the film is being properly driven. Should the film break, the arm 11 will be relieved of the tension of the film and hence the spring 10 will draw the belt against the pulley with its full force, thereby driving the reel at its highest speed, which is of course higher than the speed at any stage of the winding of the film.

30 The tension of the spring 19 is so adjusted that the centrifugal force of the arms 17 will be sufficient to overcome the tension of the spring when the reel is rotating freely as described. When the arms 17 are thrown outward by the excessive speed of their shaft the pointed ends will scrape over the serrations 18 producing a sound not unlike a "campaign rattle", which will at once attract the operator's attention so that he may 40 stop the machine or otherwise remedy the difficulty. As soon as the speed of the reel shaft is reduced to normal, the spring 19 draws the arms 17 inward out of contact with the serrations.

50 I have described my improved signal device in connection with the most improved film controlled driving mechanism of the lower reel, but it is obvious that it may be used to advantage in connection with other forms of reel driving mechanism. The most simple form of driving mechanism now in use is an ordinary slip clutch through which the reel shaft is driven from a constantly rotating pulley rotating at a constant speed higher than the maximum winding speed of the reel. In this form of driv-

ing mechanism the tension of the driving reel is not increased by the breakage of the film, but the breaking of the film leaves the reel free obviously to be driven at the speed of the pulley and causes the sounding signal to be operated.

Having thus described my invention, what I claim and desire to secure by Letters Patent is:

1. The combination of a magazine for moving picture films having a door adapted to close the magazine, a winding reel within the magazine and an indicator carried by the door and comprising a shaft rotatably mounted in the door and having a driving connection with the winding reel when the door is closed and a speed controlled signal operated by said shaft to produce a signal when the speed of said shaft exceeds a predetermined maximum.

2. The combination of a magazine for moving picture films having a door adapted to close the magazine, a winding reel within the magazine, an indicator carried by the door of the magazine and having operative connection with the winding reel when the door is closed, said indicator comprising a speed controlled signal device adapted to operate to produce a signal when said winding reel exceeds a predetermined speed.

3. The combination of a magazine for moving picture films, a winding reel within said magazine, a tension drive for said reel, and an indicator without said magazine having operative connection with said reel, said indicator comprising a speed controlled signal device adapted to operate to produce an alarm signal when said winding reel exceeds a predetermined speed.

4. The combination of a magazine for moving picture films, having a door adapted to close the magazine, a winding reel shaft within the magazine, a tension drive for such shaft, an indicator carried by the door of the magazine and having driving connection with said shaft when the door is closed, said indicator comprising a rotary member having a part radially movable through centrifugal action and a sounding member adjacent said rotary member and adapted to be engaged by said radially movable part when said reel exceeds a predetermined speed.

Signed at New York in the county of New York and State of New York this 20th day of January, 1914.

NICHOLAS POWER.
